UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 14,505, dated December 25, 1883

Application filed July 23, 1883. Term of patent 3½ years.

To all whom it may concern.

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

15 The ground *a* is irregularly filled in with

small geometric work, as shown. Over this ground are several large flower-groups.

A has a central mass of open and star-shaped flowers and leaves and projecting blossom and fern sprays. B has a central mass of large 20 leaves and star-shaped flowers surrounded by projecting leaf and blossom sprays on all sides. Several other groups complete the design.

I claim—

The design for a carpet, substantially as 25 shown and described.

WINTHROP L. JACOBS.
